THREAD CUTTING TOOL

Albert J. Prance, Detroit, Mich., assignor to
 Murchey Machine & Tool Company, Detroit,
 Mich., a corporation of Michigan

Application July 28, 1932, Serial No. 625,313

6 Claims. (Cl. 10—103)

This invention relates to thread cutting chasers, and more particularly to an improved thread cutting device adapted to be carried by a rotatable head or holder together with one or more other 5 similar chasers, concerning itself specifically with the provision of improved means for adjustably securing the chasers in place.

An object of this invention is provision of strong and novel means for locking and supporting the 10 chasers.

A further object is provision of novel means for adjusting the position of the chaser cutting edges to compensate for wear and grinding, which adjusting means is of such strength as to easily with- 15 stand the full thrust imposed by engagement of the tool with the work.

Still further objects will readily occur to those skilled in the art upon reference to the following description and the accompanying drawing in 20 which

Fig. 1 is a sectional view of a chaser block and a chaser, showing the novel chaser adjusting means;

Fig. 2 is a section taken substantially on the 25 line 2—2 of Fig. 1 and looking in the direction of the arrows;

Fig. 3 is a side view of a somewhat modified form of chaser;

Fig. 4 is a side view of a modified form of chaser 30 driving worm wheel and connecting member adapted to cooperate with the modified chaser shown in Fig. 3.

Referring to the drawing, it will be seen that a chaser block 24 is provided carrying on its front 35 face 26 a thread cutting chaser 28 of a form to be described.

The block may be provided with abutment pins as 32 adapted to be engaged by suitable positioning means carried by the head or other support, 40 (unshown) and beveled as at 42, for engagement with an adjusting cam or the like (also unshown).

Each chaser 28 is peripherally provided with master thread ribs 50 and is cut away so that a cutting edge 54 is formed. The position of this 45 edge 54 with respect to the central axis of the chaser and with respect to the chaser head is extremely important and must be maintained uniform for each chaser when several are used. When the cutting edge 54 wears down it must be reground, and the chaser must then be rotated on its axis to return the new edge 54 to its original position. For this purpose means to rotate the chaser infinitesimal amounts on its own central axis is provided, and will now be described.

55 Chaser 28 is centrally provided with a splined

aperture adapting it to fit over the complementary splined portion 58 of the hub 62. The hub is provided with an enlarged head portion 60 in the form of a worm wheel, and is rotatably disposed within the hollow chaser block 24 in the 60 manner shown so that its splined portion 58 projects therefrom and into interlocked engagement with the interiorly splined aperture 56 in the chaser. The extreme end 64 of the hub member is reduced and threaded for reception of the nut 66, which secures the chaser to the block and fits within the counterbored portion 56' of the aperture in the chaser. The enlarged worm wheel portion 60 of the hub member fits within a counterbored portion 61' of the aperture 61 in 70 the chaser block, so that by tightening the nut 66 the chaser and block may be clamped together. The thread of the portion 64 is preferably made so that the nut tightens when turned in the opposite direction to that in which the chaser must be 75 turned to advance the cutting edge.

A pair of worms 68 disposed within transverse bores 72 of the chaser block engage the worm wheel 64 to enable rotating the latter infinitesimal amounts and since the wheel is locked to the 80 chase, the latter will also be rotated the same amount, as can be readily observed.

The worms 68 may be provided with inset hex counterbores as 78 whereby they may be rotated by means of an "Allen" wrench, or the like.

It will also be observed that after a chaser is 85 adjusted with respect to the block, the nut 66 may be tightened in order to clamp the chaser to the block without disturbing the setting or adjustment of the chaser, which may be very accurately fixed by reason of the use of two worms, which enable fixing the position with absolutely no "play" or looseness to introduce inaccuracies.

It will further be seen that due to the novel adjustment provided an infinite number of positions for the cutting edge can be maintained and accordingly, it is not necessary to grind the cutting edge any more than is necessary to sharpen it, there being no grinding back for positioning the cutting edge as is the case with other forms 90 of chasers well known in the art rotatably adjustable only in steps.

It will further be observed that each chaser is provided with a broad continuous peripheral chamfer 80, thus eliminating the necessity of 105 providing a new chamfer on the chaser when the cutting edge is being ground.

Any strain on the chaser cutting edge 54 not absorbed by the block 24 against which the chaser is clamped is transmitted to the worms 68 thru 110

the hub and the wheel 64, but by using two of these in the manner shown, adequate strength to insure their long life is obtained, and since they are comparatively inexpensive and readily replaceable, this is unimportant in any event. Maintenance of the chasers in thread cutting machines is thus made a very simple and inexpensive matter.

In Figs. 3 and 4 there is disclosed a modification in which the chaser 90 is provided with integral lugs 92 projecting from its rear surface. The hub 94 and worm wheel 96 are formed as a unit, and the hub carries slots or crown clutch teeth 98 with which the lugs are adapted to interfit. The chaser and hub member are axially bored, as at 99 and 100 respectively, and may be secured together in position and to the chaser block by means of a nut and bolt (not shown).

Now having described the invention and the preferred embodiment thereof, it is to be understood that said invention is to be limited, not to the specific details herein set forth, but only by the scope of the claims which follow:

What I claim is:

1. In a chaser head construction, a chaser block, a chaser shaft journaled in the block and having an end exposed at the front of the block, a chaser, screw-threaded securing means for securing the chaser upon the front of the block and to said end of the shaft, said securing means being accessible from the front of the chaser and being adapted when tightened to clamp the chaser against the block, and means for rotating the chaser to adjust the position of its cutting edges, said means including a worm wheel attached to said chaser shaft, and a worm carried by the block and engaging the worm wheel.

2. In a chaser head construction, a chaser block, a chaser shaft journaled in said block and having a free splined and screw-threaded extremity at the front of the block, a complementarily splined chaser mounted on said shaft in front of the block, screw-threaded means accessible from the front of the chaser for securing the latter upon the shaft and clamping it against the block, and means for rotating the shaft and so the chaser to adjust the position of the chaser cutting edges, including a worm wheel connected to the shaft, and a worm mounted in the block and engaging the worm wheel.

3. In a chaser head construction, a chaser block, a chaser, a combined chaser shaft and clamping bolt journaled in said block and carrying the chaser upon its front end, the chaser

55

overhanging the block, a head portion carried by said combined shaft and bolt member and arranged behind a part of the block, and means engaging said head for rotating the latter and so the chaser shaft and chaser to adjust the position of the chaser cutting edges, and means for clamping the head and chaser against opposite surfaces of the block.

80

4. In a chaser head construction, a chaser block, a chaser shaft journaled in the block and having a free screw threaded extremity at the front of the block, a chaser, means for securing the chaser to the shaft in any of various positions and for clamping the chaser against the block, including screw threaded means manipulatable from the front of the chaser and cooperatively engageable with the screw threaded extremity of the shaft, a worm pinion carried by a rear portion of said shaft, and a worm journaled in the block and engaging the pinion to enable turning the shaft and so turn the chaser with respect to the block to change the position of the chaser cutting edge.

85

5. In a chaser head construction, a chaser block, a combined clamping bolt and hub member journaled in the block and having an exposed end accessible from the front of the block, a chaser, a head portion carried by said combined bolt and hub member and overhanging a rearwardly facing surface of the block, screw threaded means for securing the chaser to the hub and for clamping the chaser to the front face of the block, a pinion carried by said head portion of the combined bolt and hub member, and a worm in the block engaging the pinion to rotate the latter and so the chaser and hub assembly as a unit with respect to the block for adjusting the position of the chaser cutting edges.

90

6. In a chaser head construction, a chaser block, a combined supporting hub and clamping bolt journaled in the block, a chaser, screw threaded means for securing the chaser to the end of the hub, a head portion carried by said combined hub and bolt, a pinion carried by said head, the hub and chaser being provided with selectively interengageable portions whereby they are non-rotatable with respect to each other when assembled, and a worm in the block engaging the pinion to rotate the same and so the hub and chaser assembly as a unit with respect to the block, for adjusting the position of the chaser cutting edges.
